UNITED STATES PATENT OFFICE

2,571,567

LINE INDICATOR AND COPYHOLDER

George Greenberg, Brooklyn, N. Y.

Application July 10, 1946, Serial No. 682,669

10 Claims. (Cl. 116—119)

1

This invention relates to line indicators when copying a manuscript or other material, or when working on an accountant's sheet or book or the like, and it also aims to combine such a device with a holder for the copy or sheet on which the lines are to be indicated by the device.

As it is well known, when a manuscript or other original is to be copied, like by a typist, and also when accountants work on sheets or books of accounts, a ruler or the like is placed at the line to which the work progressed, as otherwise, repetitions, omissions, or other mistakes may occur. At present, simply a ruler, an eraser, or any other object is placed at the line to which the work progressed, to know where to take it up again, and it is obvious that such a flimsy, make-shift indicator or marker is adapted to change its position, and to slip, whereby it will defeat its own purpose. Such indicators, for the purpose mentioned, are also objectionable, as they do not indicate the line or the place with the clearness and exactness required in some work, and the line or item arrived to as the work progresses, cannot be easily and clearly observed.

The main object of my invention is to provide a device for indicating lines or places arrived to in copying or in working on accounts and the like, which will be more efficient than those now in use or heretofore proposed.

Another object of my invention is to provide a device of the type described, which will be less complicated in construction than some of the devices proposed for this purpose, and which simply may be placed on the sheet or book, a portion of which is to be marked, and still will remain in place in a reliable manner, indicating that place, and which also may be removed with the same ease and facility.

Still a further object of my invention is to provide a device, as characterized hereinbefore, which will be adapted to be clamped on a sheet or several sheets, or a book and the like, worked on, whereby it will hold such a material against movement.

Still further objects of my invention will be apparent as the specification of the same proceeds, and, among others, I may mention: to provide a device of the mentioned character which will be simple in construction, inexpensive, and adapted to mass manufacturing.

With the mentioned and other objects in view, my invention mainly consists in providing an elongated weight which is adapted to be placed at one side of the sheet or book worked on, and

2

on which an indicator arm may slide. Said weight also may include a telescopic inner weight, whereby the length of the same may be adjusted according to the length of the sheet worked on.

5 In the drawings, forming a part of this specification and accompanying the same,

Fig. 1 is a plan view of a sheet to be worked on, and a preferred embodiment of my device placed thereon;

Fig. 2 is a sectional view, the section being taken on the line 2—2 of Fig. 1;

Fig. 3 is an end view of my device, as indicated by the line 3—3 in Fig. 1, and

Fig. 4 is a fragmentary sectional detail, the section being taken on the line 4—4 of Fig. 2;

Figs. 5 and 6 show details of a modification.

Referring now to the drawings more in detail by characters of reference, the numeral 10 indicates my device, in general, being placed on a sheet to be copied or to be worked on, indicated by the numeral 11, and having lines or other items 12.

The main element of my device is a bar 13, having considerable weight, and slidably in an inverted U-shaped sleeve or jacket 14.

It will be seen that the weight has a relatively narrow base 15, and comparatively high side walls 16, while the top 17 of the same is rounded.

10 To make the same easily slidable in the shell or sleeve 14, said sleeve is loosely arranged therearound, but the base weight 13 will have a groove or indentation 18, at each side of the same, and the outer sleeve or shell 14 will have a registering indentation 19, whereby the inner weight 13 may easily slide inwardly or outwardly of the sleeve 14, as indicated by the double arrow 20, but it still will be guided in its movements and will keep the outer sleeve 14 in the desired fixed relation thereto.

An inverted U-shaped band 21 is slidable on said outer sleeve 14, said band having an integral transverse arm 22 projecting from the lower end of its branch 21a, and slightly above the bottom 15 of the weight 13, whereby said arm may slide upwardly and downwardly over the sheet 11, but in close proximity to the same, so as to be adapted to mark any item or line 12, as will be understood. Band 21 may have indentations 23 to better secure its position on the sleeve 14 and on the base weight 13, when it will be sliding thereonto, as will be explained presently.

The top portion 21b of the band 21 is considerably spaced apart from the top 17 of the sleeve, and, of course, from the top 13a of the base

weight 13, and a spring wire 24 is secured thereto, adapted to press downwardly on said sleeve, or on the base weight 13, thereby assuring the position of the band by frictional action. The band, namely, will have inwardly projecting rounded portions 25, to the rear of said indentations 23, and opposite the groove 18, in the base weight, and 19, in the sleeve 14 respectively, and thereby an upward movement of the band 21 will be prevented. A felt, or rubber, sheet 26 also may be secured on the bottom 15 of the weight 13, whereby slipping or sliding on the sheet 11 will be prevented, in addition to the frictional action of the weight itself.

The use and arrangement of my device for the purpose mentioned will be obvious from the herein description, and from the drawings.

The weight 13, entirely telescoped into the sleeve 14, will be placed on one side of the sheet 11, in Fig. 1, the right side being indicated, on a free marginal portion thereof, having no text, figures, or any other material on said margin. As the copying or observing of the items progresses, the band 21 will be moved downwardly along the sheet or page 11, as indicated by the arrow 27, and the arm 22 will indicate the place where the work has to be resumed.

The pressure of the spring 24 may be selected in such a manner that the band 21 may comparatively easily slide on the sleeve 14, but said spring will fix it in the position to be moved.

When the sheet 11 is longer than the sleeve 14, the base weight 13 will be moved out from the same, as indicated by the dot and dash lines in an imaginary manner at 13b in Fig. 1, and when the indicator 22 arrives to the lower end 14a of the sleeve, it then continues its downward movement over the extension weight 13.

A band 21 will have the rounded portion 25, riding in the grooves 18 and 19 respectively and by its rounding in both directions, the band 21 may easily move from the sleeve 14 to the weight 13, or, vice versa, in the other direction, when it is desired to again contract and telescope the device.

When the band 21 rides on the weight 13, the spring wire 24 will move somewhat downwardly and still retain a pressure on the weight 13. To allow such a movement for the spring 24, a slot or window 28 will be provided in the band 21, the outer end 24a of the spring being allowed to move upwardly and downwardly in said window.

My device is adapted to be placed on the left hand side of the sheet 11, when desired, said place for the same being indicated by the numeral 29.

In some cases, the right hand side of the sheet will not have sufficient free margin to place the indicator weight bar thereon, and the left hand side may allow such a placing of the same without interfering with the material on the sheet. In such cases, band 21 will be entirely pulled off the sleeve 14, whereupon the weight with the sleeve on it will be placed on the left side margin of the sheet, as indicated by 29, and the band 21, pushed thereon in a reversed manner, so that arm 22 will then point to the right of the weight bar, instead of pointing to the left, as now indicated in Fig. 1.

The use and operation of the device will be identical as described with reference to said right hand original position of the same.

Finally, I also may provide means whereby my device, in addition to its weight, may also be clamped on the sheet 11, or on a book, if such

is the object worked on, or, indeed, may clamp the sheet on the book to a supporting element like the top of a desk. For this purpose, the sleeve 14 may have narrow extensions 30, and a spring clamp 31 may be pushed over them and underneath the sheet, book, or other object 32, and in this manner my device will be secured to the object 32, and if said object is composed of pages of a book, loose sheets, or even a single sheet, the same may be secured against accidental motion with reference to my device 10.

Clamp 31 will be employed when desired, as my device may perform its object without such clamping, and it also will be obvious that the same clamping means may be used when my device is placed on the left hand margin 29, only clamp 31 will be employed in an opposite direction. Indentations 33 may also be provided at the outer end of the weight 13, to facilitate its moving inwardly or outwardly on the shell 14.

While I have shown preferred embodiments of my invention, it is to be understood that changes and variations may be resorted to in the elements, construction and combination of it, and I reserve my rights to such changes and variations as are within the spirit of this specification, and the scope of the claims hereunto appended.

One such change is shown in Figs. 5 and 6, and, as will be seen, a sliding slip 34 may be arranged on the arm 22, in case it is desired to indicate not only the line to which the work progressed, and which is indicated by the arm 22, but also indicate on said line an item to which the slip 34 may be pushed on the arm 22, as will be understood.

What I claim as new, and want to protect by Letters Patent of the United States, is:

1. A line indicator comprising, in combination, a substantially heavy bar having a plane base, being substantially higher than the width of its base and adapted to be placed on a page of a book or a sheet of paper or other material by said base, a resilient loop of a strip of material encircling the top and sides of said bar, the lower ends thereof being slightly above said base, and said strip being slidable on said bar while pressing on its sides, and a lateral arm bent out to one side from said strip at one of its lower ends whereby said arm is adapted to indicate a line on said page of a book or sheet of material.

2. In a device, as set forth in claim 1, the top of said loop being spaced apart from the top of said bar, and a downwardly curved flat spring adapted to slidably press on the top of the bar secured by its ends in the top of said loop, whereby said loop will be removably secured in its various positions when sliding on said bar by the frictional action of said spring on the top of the bar.

3. In a device, as set forth in claim 1, longitudinal grooves in the sides of said bar and corresponding beads in said loop, in complementary sliding engagement with said grooves.

4. In a device, as set forth in claim 1, said loop being entirely removable from said bar by sliding it off the same and being adapted to be similarly replaced in a reversed position, its arm pointing oppositely, whereby said line indicator may be employed on either margin of a sheet or a book and the like.

5. In a device, as set forth in claim 1, means at one end of the device whereby to clamp it on said page of the book or a sheet of material when desired.

6. In a device, as set forth in claim 1, said bar

having a top and two sides, an outer shell encircling the top and the two sides of said bar, said bar being slidable therein, and said resilient loop being adapted to ride on said outer shell, or on said bar when pulled out from said shell.

7. In a device, as set forth in claim 6, a longitudinal groove in said bar and a complementary bead in said shell telescopically and slidably engaging one another, and said spring loop having a similar bead adapted to slide in the groove of the bar or in the bead of the shell.

8. In a device, as set forth in claim 6, indentations in the sides of said bar in an end portion thereof, usually projecting from said shell, said bar being adapted to be gripped at said end thereof through said indentation for slidably moving the bar inwardly or outwardly from said shell.

9. In a device, as set forth in claim 6, the top of said resilient loop being spaced apart from the top of said shell and said bar, and a downwardly curved flat spring adapted to slidably press on the top of the shell or on the bar, respectively, secured by its ends in the top of said loop whereby said loop will be removably secured in its vari-

ous positions when sliding on said shell or on said bar by the frictional action of said spring on the top of the shell or of the bar.

10. In a device, as set forth in claim 5, said means consisting of extensions at the end of the shell adapted to be clamped, as recited.

GEORGE GREENBERG.
